UNITED STATES PATENT OFFICE.

EDWARD CHARLES SPURGE, OF NIAGARA FALLS, NEW YORK; LOUISE T. SPURGE,
GEORGE EMERSON COX, AND GEORGE SLATE, JR., ADMINISTRATORS OF SAID
EDWARD CHARLES SPURGE, DECEASED.

OZONIZER.

1,071,476.

Specification of Letters Patent. Patented Aug. 26, 1913.

Application filed July 17, 1912. Serial No. 799,877.

To all whom it may concern:

Be it known that I, EDWARD C. SPURGE, a subject of the King of Great Britain, residing at Niagara Falls, in the county of Niagara and State of New York, have invented certain new and useful Improvements in Ozonizers, of which the following is a full, clear, and exact description.

This invention relates to ozonizers and 10 has for its object the construction of a device of this character which shall be adapted to be safely used by unskilled persons and in which to this end no parts at high electrical tension are exposed or left uncovered.

15 Another object of my invention is to provide a structure of the character in question in which the dielectrics, which even under the most favorable conditions are occasionally subject to puncture by reason of the 20 high voltages used, may be readily removed and replaced.

The preferred construction involves relatively few and inexpensive parts which 25 coact to afford an apparatus which in practice has demonstrated its high efficiency.

The dielectrics in ozonizers are apt to become overheated and are hence rendered more liable to rupture. Various attempts have been made to provide cooling means to 30 the end that this tendency may be overcome. I am aware, for example, that it is known to provide hollow gas-cooled or water cooled electrodes, and also to sprinkle water upon cooling parts used in devices of this description, and I hence make no claim broadly 35 to the cooling means, *per se*, employed in my ozonizer; but I do contend that the particular disposition of parts with respect to each other is novel and avoids certain objectionable features and characteristics usually 40 present in devices of this character as heretofore constructed.

These and other objects of my invention will be hereinafter referred to and the novel 45 combinations of elements whereby they may be attained will be more particularly pointed out in the appended claims.

In the accompanying drawings which 50 form a part hereof and in which like reference characters designate like parts throughout the several views I have shown a preferred construction; but I am aware that various changes and modifications may be made therein without departing from the

spirit of the invention and hence desire to 55 be limited only by the scope of the said claims.

Referring to the drawings: Figure 1 is a plan of an ozonizer, partly broken away to expose the interior thereof; Fig. 2 is a plan 60 of the inner side of one of the combined water-cooled casings and electrodes, the water chamber being partly broken away; Fig. 3 is a side view of the ozonizer, a water pipe and its coupling therein being shown partly 65 in section; Fig. 4 is a section, drawn to an enlarged scale, taken on line IV—IV of Fig. 1.

The preferred construction provides a separable two-part casing, the respective parts 70 1, 2 of which also constitute the grounded electrodes. These electrodes are hollow so as to adapt them to be water-cooled, the chambers 3 therein being in communication with each other through a short U-shaped 75 pipe 4, provided with a coupling 5. The disposition of this pipe being best shown in Fig. 3 and the respective extremities thereof communicating with short conduits 6 which open into the chambers 3. For simplicity of 80 construction the conduits may be cast integral with the chambers; and each casing may be provided with a flange 7 to adapt it to be bolted to its companion. A suitable gasket 8 may be disposed between these 85 flanges in order to space them apart the desired amount and make the casing air tight. Between the outer surfaces of the inner walls 9 of the chambers 3, are disposed dielectrics 10 and an electrode 11. The latter 90 preferably consists of a sheet of tin or composition foil, or some like electrically conductive material adapted for the purpose in question; and the dielectrics 10 may consist of sheets of glass, micanite, or other suitable 95 material of sufficient thickness and dielectric strength to successfully withstand the relatively high voltages to which these parts are subjected.

As indicated at 12', the electrode 11 does not extend quite out to the 100 edge of the dielectrics, and it is to be particularly noted that the dielectrics are preferably cemented or otherwise secured directly to the surfaces of the electrode, so that no air space occurs therebetween. As 105 a matter of fact, in assembling these parts, considerable care is exercised to, as far as practicable, eliminate even any small pockets

of air or bubbles which tend to form when the plates are being pressed together; the reason for this being that if air is present it tends to expand when heated, and otherwise results deleteriously to the apparatus in several ways, as for example, by corroding the electrode.

Especial attention is also directed to the fact that the dielectrics and electrode 11, in effect, constitute a unitary structure, since when the apparatus is opened they are removed or replaced as a unit. Spacers 12 separate the dielectrics from the adjacent walls 9 of the water-cooled electrodes. As best shown in Fig. 1, these spacers may be simple strips, preferably of insulating material, such as micanite, mica, or glass, which are cemented or otherwise secured to the outer surfaces of the dielectrics so that these spacers also constitute parts of the unitary structure above referred to. The spacing strips 12 may be disposed on the diagonals of the preferably square dielectrics; but, as shown in Fig. 1, do not extend quite to the center thereof in order to provide sufficient space between their interior extremities to permit the ozone to flow freely out into the collecting conduits 13 provided therefor in the water-cooled electrodes. As indicated in Fig. 4, suitable pipes 14 may be tapped into or otherwise secured to the mouths of these conduits whereby to convey away the collected ozone; and it will be noted that the ozone conduits are disposed, in the preferred form of the device, substantially centrally of the electrodes.

In order to hold the dielectrics against lateral displacement when in position between the hollow electrodes, insulating blocks 15 may be provided upon either side of the dielectrics and at the bottom thereof; these blocks being secured to the casing 2 by means of screws 16.

Preferably near the top of one of the casings, to wit, that designated 2, is an aperture 17 adapted for the reception of the stem of an insulating headed or shouldered bushing 18. Secured within the latter is a glass tube 19 filled with insulating material 20, embedded in which latter is a conductive rod 21. Rod 21 constitutes the binding-post for the electrode 11, the outer extremity thereof being provided with nuts 22 between which may be clamped a lead 23 from the transformer or other source of high potential current used. The inner extremity of the rod 21 is correspondingly threaded and provided with nuts 24, between which may be secured the extremity of a pig-tail 25, of fine wires, which extends out between the dielectrics from the electrode 11.

The water, whereby the grounded electrodes are cooled, may be led in from a pipe 26 through the corresponding conduit 6 into the chamber 3 of the casing 1, thence out

through a conduit 6 opposite that through which the water enters, through the pipe 4, to the opposite electrode; emerging from the chamber 3 of the latter via an exit pipe 27. The pipes 26, 27 may be connected to the casing by means of suitable bushings 28, and for convenience of construction, four bosses or lugs 29 (within which are disposed the conduits or recesses 6) are provided in each casing part 1, 2; those conduits or recesses not used being closed at their outer extremities by plugs 30. The flanges 7 of the respective halves of the casing are separably held together by screws 31, or the like. The insulating stud 18 is secured in place by a single nut 32, the removal of which, after the casing has been opened, permits of the immediate withdrawal of the binding post and its associated parts through the aperture 17, and since the dielectrics are merely loosely held between the walls 9 with their respective edges in engagement with the insulating blocks or supports 15, the combined dielectrics and electrode together, if desired, with the terminal of the latter, may be freely and readily removed from the apparatus. The construction whereby this is made possible is of very great importance, since in operation, despite the cooling action exerted upon the dielectrics in the manner hereinafter described, such parts are occasionally subject to puncture or rupture owing to the severe electric stresses imposed thereon; in which event, of course, it is desirable to effect the removal of the injured parts with the utmost facility. Even one unskilled in the art and having but rudimentary mechanical knowledge or skill may replace a broken down dielectric by merely unscrewing screws 31, which permits of the separation of the casing halves and then loosening nuts 24. This loosens the wires connecting with the high tension electrode and makes it possible to lift the dielectric unit out. A new dielectric unit may then be inserted, the old terminal being again utilized, if desired.

Both of the cooled electrodes are grounded, as indicated at 33, and the ozone pipes 14 being screwed thereinto, are also grounded. It is to be observed that the arrangement of parts employed is such as to substantially completely inclose the electrode 11 and the parts in electrical communication therewith.

The ozonizer casing may be mounted directly upon the top or side of a casing 34 within which may be disposed the transformer, if the latter be the source of current employed, in which case even the outer end of the terminal is so inclosed as to render inadvertent contact therewith impossible. It has not been thought necessary to indicate the transformer or connections therefrom, since the casing 34 has been

characterized in the drawings by the words "transformer casing."

Resumé.—I especially desire to direct attention to the following points which I regard as of particular importance. In my construction, the electrode 11 is hermetically sealed between two sheets of dielectric material and is removable therewith from the casing as a unit. Each grounded electrode 10 is water-cooled, whereas the other electrode is cooled by radiation, whereby to reduce the likelihood of short-circuiting. The two dielectrics are not directly cooled and do carry no conducting material on their exterior surfaces, but instead have the electrode cemented or sealed between their interior surfaces. No air space is provided between the dielectrics and the electrode between them. Ozone is generated only in the 20 spaces between the exterior surfaces of the dielectrics and the adjacent water-cooled electrodes. The ozone as generated is collected and drawn off through the centrally disposed conduits 13. If desired, air may 25 be admitted through one conduit 13; the ozonized air or ozone being drawn off from the ether of these centrally disposed conduits. When the apparatus is used in this 30 fashion, the air is subjected to the action of the electric discharge first upon one side of the dielectric unit and then on the other side of the same. Air may also be admitted through an opening 35 in the casing, directly to the channel 36 provided around 35 the water boxes or chambers 3, in which case the ozone may be drawn off through both of the pipes 14. The advantage of the channeled formation of the casing is that in any case it tends to promote an equable 40 flow of air over the dielectrics. Finally, it should be mentioned that by making the electrode 11 of very thin foil, as for example of one thousandth of an inch in thickness, the liability of the dielectrics to become 45 loosened therefrom due to expansion and contraction of the metal, is substantially eliminated; while even though this metal

be of such extreme thinness, there is practically no chance for it to be injured or destroyed by the acid or acids usually present 50 in the vicinity of high tension discharges through air, since no air is in contact with the faces of the foil.

Even dry air will oxidize an electrode of the type in question if permitted to come 55 in contact therewith during the electric discharge, and moist air is usually most deleterious. The casing of the ozonizer being of cast metal, and its construction such as to be easily made air tight, allows the 60 use of dried air, which is very beneficial, either under a pressure as great or greater, or less than that of the atmosphere. It also easily permits pure oxygen or other 65 gases being submitted to the electric discharge.

Having described my invention, I claim:

1. The ozonizer which comprises a separable casing the parts of which are hollow and constitute one of the electrodes of the 70 ozonizer, connections to said casing for passing water through said hollow parts, a unitary structure consisting of another electrode sealed in between dielectrics, portions, at least, of said dielectrics being 75 spaced from said casing parts to provide an air space within which the ozone may be generated, and means for conducting ozone from said casing.

2. An ozonizer comprising a two-part 80 casing constituting one electrode, in combination with a unitary structure consisting of two dielectrics and an electrode between them, the unitary structure being clamped between the parts of the casing in a manner 85 to provide discharge gaps on each side of the unitary structure.

In witness whereof, I subscribe my signature, in the presence of two witnesses.

EDWARD CHARLES SPURGE.
